UNITED STATES PATENT OFFICE.

FRANK CLAYTON BROWN, OF LAURIUM, MICHIGAN.

CATALOGUE.

1,286,522.

Specification of Letters Patent.

Patented Dec. 3, 1918.

Application filed March 26, 1917. Serial No. 157,316.

To all whom it may concern:

Be it known that I, FRANK CLAYTON BROWN, a citizen of the United States, residing at Laurium, in the county of Houghton and State of Michigan, have invented certain new and useful Improvements in Catalogues, of which the following is a specification.

In the usual catalogue or price list the articles are arranged or classified according to their nature or in accordance with some arbitrary system. The pages of the catalogue are numbered and usually an index is provided. In the index the articles are customarily listed in alphabetical order with references to the pages of the catalogue. A person desiring to look up the catalogue description or price of an article first consults the index and then turns to the page given in the index. Upon this page there may be a large number of articles.

One object of the present invention is to provide an indexed catalogue by means of which a person using the catalogue will be clearly referred to the particular point in the catalogue where the article in which he is interested will be found described or priced.

When using the ordinary catalogue, it is necessary to make some calculation in order to determine the price of the desired quantity if the quantity be greater than the unit quantity. Moreover, in making out an order from the usual catalogue, it is necessary for the purchaser to write out at more or less length, a statement of the kind and quantity of goods desired.

Another object of the present invention is to provide a catalogue wherein the different kinds and quantities of articles are given a concise designation so that in ordering goods from the catalogue, the purchaser need merely use a certain designation which definitely indicates to the seller not only the kind, but also the quantity intended to be ordered.

The drawing represents two pages of a book forming a catalogue, a catalogue and an index sheet for the catalogue embodying the features of my invention.

While the example given in the drawing is a grocery catalogue, it will be understood that the invention is not limited to use with any particular line of merchandise.

For the sake of brevity, only four different sorts of groceries are listed in the cata-

logue shown in the drawing, namely, tea, sugar, butter and grape juice. It will be noted that each distinct article is given an individual number, for example, uncolored Japan tea is numbered 1 and English breakfast tea is numbered 2. The articles are listed in the catalogue in numerical order.

In order that the quantity desired by the purchaser may be definitely and concisely indicated, each quantity in which a given article is sold is given a specific designation; for example, a one-pound can of uncolored Japan tea is designated in the catalogue as 1A1 and may be so designated in the purchaser's order. The first numeral 1 indicates the article and the last numeral 1 indicates the quantity. A further example of this method of indicating kinds and quantities will be found in the drawing under the heading "Sugar", wherein it will be noted that 10A1 denotes 25 pounds of pure granulated sugar, that 10A2 designates 50 pounds of pure granulated sugar, and that 10A3 stands for 75 pounds of pure granulated sugar.

The price of each quantity of each article is preferably stated in close association with each such quantity, as will be evident from an inspection of the drawing.

In many lines of business, price changes require the issue of catalogues at frequent intervals. In order that the seller shall know from which issue a given order was made out, the designation for each particular kind and quantity of article may, if desired, comprise an element or symbol identifying the catalogue issue. In the example shown in the drawing, each designation contains a letter A which may be assumed to denote the January issue of the catalogue. In the February issue of the catalogue, the item designations may be the same as those used in the January catalogue, save that the letter B is substituted for the letter A.

The index herein shown is alphabetically arranged. In connection with each article listed in the index is the number under which that article will be found listed, described, or priced in the catalogue.

It will be apparent that a catalogue arranged in accordance with the present invention is exceedingly convenient for both seller and buyer. Not only the kind, quality or grade of goods desired, but also the quantity are unmistakably indicated by a single designation.

It is unnecessary for the buyer to write out the name of the article desired or to state the quantity desired, since both are denoted by a single designation. The present invention obviates all danger of failure to indicate the quantity desired or the particular kind, quality or grade, since each kind, quality, grade and quantity has its own specific designation.

10 In the appended claims I have, for the sake of brevity, used the term "kind" to denote the kind, quality, grade, size, color or other attribute of an article.

I claim as my invention:

15 1. A catalogue comprising one or more pages having a plurality of articles listed thereon, the different articles each having a key number for purposes of designation, arranged in numerical order for the purpose 20 of location, each listed article having associated therewith a special designation indicating an arbitrary quantity in which the

article is to be sold, said special designation, when combined with the key number, indicating the location of an article and a definite quantity thereof. 25

2. A catalogue comprising one or more pages having a plurality of articles listed thereon, the different articles each having a key number for the purpose of designation, 30 the numbers being arranged numerically for the purpose of location, each listed article having associated therewith a special designation indicating an arbitrary quantity in which the article is to be sold, said special 35 designation, when combined with the key number, indicating the location of an article and a definite quantity thereof, and an index sheet having a list of the articles arranged in alphabetical order and containing the designation numbers of the respective articles. 40

In testimony whereof, I have hereunto set my hand.

FRANK CLAYTON BROWN.
